COP WINDING MACHINE

Alfred R. Wood, Bridgeport, Conn., assignor to
 The Singer Manufacturing Company, Elizabeth,
 N. J., a corporation of New Jersey

Application September 10, 1948, Serial No. 48,662

7 Claims. (Cl. 242—22)

1

This invention relates to cop winding machines of the type adapted to produce cops of thread wound by the so-called "Fiji" or "Wardwell" method of winding, in which, after the cop has been started on a suitable spindle, each turn of the thread overlies a previous turn and thereby binds together all the turns of the thread and prevents spilling. This method of winding is shown and described in the United States reissue patent to S. W. Wardwell, Jr., No. 11,856, 10 September 18, 1900.

This invention has as an object to provide an improved and simplified machine for winding cops in the above described manner.

Another object of the invention is to provide a relatively small cop winding machine which may be driven from any suitable source of power or which may be applied to a sewing machine, as an attachment, and actuated from the usual machine-driving belt, and which will automatically wind a cop during the operation of the machine and having the new cop available when required by the sewing machine.

Still another object of the invention is to provide an improved cop winding machine which may be put into operation by an operator and which will automatically be thrown out of operation and brought to rest when the winding of the cop has been completed.

A still further object is to provide in an automatic cop winding machine, simple and effective manually actuated means for removing a completed cop from the machine and for severing the thread between the completed cop and the source of thread supply.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 is a front elevation of the improved cop winder.

Fig. 2 is a left end view thereof.

Fig. 3 is a plan view.

Fig. 4 is a right end view with the driving pulley shown, in full lines, as contacting a driving element and, in dotted lines, in engagement with a suitable brake.

Fig. 5 is a rear elevation of the improved cop winder, with portions thereof broken away, and

2

a thread-laying finger shown in full and dotted lines in its two extreme positions.

Fig. 6 is a vertical section on the line 6—6 of Fig. 1.

5 Fig. 7 is a detail sectional view on the line 7—7 of Fig. 4 showing a frame locking means hereinafter described, the parts being shown in the positions they occupy when the machine is in operation.

Fig. 8 is a fragmentary sectional view of the frame-locking means, showing the parts in the positions they occupy when the machine is at rest.

Referring more specifically to the drawings, 15 the invention is disclosed as embodied in a cop winding machine comprising a base 1 which may be secured to any suitable support S, as for example, by screws 2 passed through apertures 3 (Fig. 3) and threaded into the support. The 20 base is formed with upstanding lugs 4 which carry pintles 5 on which is mounted, for slight oscillatory motion, a U-shaped frame F comprising a bottom portion 6 and upstanding arms 7 and 8. Journaled in bearings in the upper 25 ends of the arms 7 and 8, but held against endwise movement therein, is a spindle 9, which carries, at one end, a driving wheel 10 adapted, at certain times, to contact and be driven by a suitable driving member 11. This driving member 30 may be the usual driving belt of a sewing machine or any other suitable member which will transmit continuous rotary motion to the wheel 10 and spindle 9.

The end of the spindle opposite to that which 35 carries the driving wheel 10 projects beyond the bearing in the arm 8 and is reduced and squared as indicated at 12. This reduced end portion of the spindle is adapted to have thread T wound thereon to form a cop C as indicated in Fig. 1. The outer extremity of the reduced portion 12 40 of the spindle carries a bunch of closely nested wires w between which the beginning end t of the thread T may be inserted to cause the thread to be wound on the spindle by rotation of the latter.

45 Journaled for oscillation and endwise movement in the lower portions of the arms 7 and 8, parallel to the spindle 9, is a bar 13 to the outer free end of which is secured a block 14 which carries an upstanding thread-laying arm 15. This arm carries a thread-retaining wire clip 16 and is formed at its upper end with a thread-guide in the form of a notch 17.

50 Mounted in the upstanding arm 7 of the frame F, and held thereon by a set screw 18, is a pin

or stud 19 on which is journaled a combined gear and cam unit 20. This unit comprises a heart-shaped cam 21 and a relatively large gear 22. The unit 20 is rotated from a pinion 23 secured upon the spindle 9 by a set screw 24. The ratio of the pinion 23 to the gear 22 is slightly greater than 1 to 2. Specifically, the pinion 23 preferably is provided with thirty-six teeth while the gear 22 has seventy-one teeth; thus the gear 22 and the cam 21 carried thereby, are given slightly more than one rotation for each two rotations of the spindle 9 and pinion 23. Stated conversely, the spindle 9 has slightly less than two rotations for each complete rotation of the gear 22 and the cam 21. The spindle 9 is held against endwise movement relative to the frame F by the hub of the driving wheel 10 and the gear 22 engaging opposite sides of the arm 7 of the frame.

Pivotedly mounted on a horizontally disposed pin 25 carried by the arm 8 of the U-shaped frame F, is a bell-crank lever L having a substantially horizontal arm 26 and a substantially vertical arm 27. The arm 26 of the bell-crank lever L engages, and is actuated by, the periphery of the cam 21. Preferably, but not necessarily, contact between the arm 26 and the cam 21 is effected through the medium of a ball-roller 28 carried by the arm. This construction reduces the friction between the cam and the arm and effects easier and smoother action. The arm 27 of the lever L carries an extension piece 29 which has its lower end pivotally connected, at 30, to one end of a horizontally disposed link 31. The other end of the link is pivoted, at 32, to the side of a horizontally disposed U-shaped yoke 33 journaled on the bar 13 at opposite sides of collars 34 and 35 secured upon the bar. From the foregoing it will be understood that rotation of the cam 21 will effect oscillation of the bell-crank lever L which, in turn, will effect endwise reciprocation of the link 31, yoke 33, bar 13, and lateral movement of the thread-laying arm 15, while permitting the bar 13 and arm 15 to be turned relative to the yoke 33. A coil spring 36, connected at one end to the arm 8 of the frame F and at its other end to an extension 33a of the yoke 33, tends to shift the yoke, the link 31 and the lower end of the arm 27 of the bell-crank lever L to the left, as seen in Fig. 1, and thereby maintains the ball-roller 28 in contact with the periphery of the cam 21.

The bar 13 and the thread-laying arm 15 are urged to turn in a counterclockwise direction, as seen in Fig. 2, by the action of a coil spring 37 which is connected, at one end, to an extension 19a of the pin 19 and, at its opposite end, to a trip-finger 38 carried by the bar 13. Thus when the machine is out of operation, the upper portion of the arm 16 rests against the squared portion 12 of the spindle upon which the thread is to be wound.

When the machine is to be put into operation the thread T is passed from a suitable source of supply, through a tension device 39, carried by the base 1, through a thread-guide 40, beneath the thread-retaining wire clip 16, through the thread-guiding notch 17 in the upper end of the arm 15, and the end portion t thereof is inserted between and gripped by the wires w at the free end of the spindle. Rotation of the spindle and endwise reciprocation of the bar 13 and lateral movement of the arm 15 cause the thread to be wound helically about the spindle as hereinbe-

fore described. As the cop C is wound the upper end of the arm 15 is pressed upon the periphery of the cop and is gradually moved outwardly from the spindle as the cop increases in diameter, turning the bar 13 about its axis.

The machine is started by tipping the frame F rearwardly on the pintles 5, in opposition to the pressure of a coil spring 41 seated in a recess 41a in the rear portion of the frame arm 7 and bearing upon the base 1, thereby causing the drive wheel 10 to be shifted from the position illustrated in dotted lines in Fig. 4 to the position shown in full lines in that figure. This causes the periphery of the wheel to be moved into driving contact with a suitable driving element such, for example, as the belt 11. Locking means is provided for maintaining the frame in this position, in opposition to the spring 41 until the cop has been wound to a predetermined diameter. This means comprises a plunger 42 (see Fig. 7) mounted in a vertically disposed bore 43 in the forward portion of the lower end of the frame arm 7. A coil spring 44 also located in the bore 43 and surrounding a reduced stem portion 42a of the plunger 42 depresses the plunger and maintains the lower end in contact with the base 1. The portion 42a of the plunger 42 is slidably fitted in a reduced bore 45 and carries a still further reduced portion 42b. A horizontal bore 46 also is formed in the frame arm 7 and intersects the bore 45. Slidably mounted in the bore 46 is an abutment member 47 having a vertical bore 48 through which the portion 42b of the plunger 42 projects. A coil spring 49 surrounding a portion 47a of the abutment member bears, at one end, against the arm 7 and at its opposite end against a head 47b formed on the member 47. This spring normally urges the abutment member 47 to the position shown in Fig. 7 in which the lower surface of the member overlies and engages a shoulder 42c provided at the upper end of the portion 42a of the plunger 42, while the upper surface thereof is engaged by the upper wall of the bore 46. In this position of the parts there is an unyielding obstruction between the top wall of the bore 45 in the arm 7 and the base 1, which prevents the frame F from being tipped forwardly, about the pintles, 5, by the spring 41. Thus the frame is held in operative position with the wheel 10 in contact with its driver 11.

As hereinbefore stated, during winding of the cop the bar 13 and the trip-finger 38 carried thereby are reciprocated back and forth while the arm 15, bearing at its upper end against the cop, causes them to be slowly turned clockwise, as seen in Fig. 2. During these reciprocations the free end of the trip-finger 38 passes idly beside and beyond the head 47b of the abutment member 47. When the cop has attained a predetermined diameter, the arm 15, bar 13 and trip-finger 38 have been turned sufficiently to shift the end of the trip-finger into alignment with the head 47b of the abutment member 47. The next rearward movement of the finger 38 causes it to push the abutment member inwardly, in opposition to the spring 49, to shift the member 47 out of contact with the shoulder 42c and to cause the bore 48 to be vertically aligned with the portion 42a of the plunger 42. When this condition is reached, the spring 41 is free to swing the frame forwardly on the pintles 5 to shift the wheel 10 out of its driver 11 and to bring it into contact with a stationary brake-shoe 50, preferably of leather, carried by an up-

standing lug 51 formed on the base 1, as shown in dotted lines in Fig. 4. The lug 51 also supports the thread-tension 39 hereinbefore mentioned. The machine comes to rest with the locking elements in the positions shown in Fig. 8.

The wound cop may be removed from the squared portion 12 of the spindle 9 by shifting it axially of the spindle and off the free end thereof. This may be accomplished by the aid of a manually actuatable cop-shifting member comprising a bell-crank lever E fulcrumed at f against the side of the frame arm 8. One arm and the fulcrum f of the lever E are normally maintained in contact with the arm 8 by the action of a coil spring 52 interposed between the lever and the head of a screw 53 which passes freely through an aperture in the lever and is threaded into the arm 8. The lever E comprises an upstanding arm 54, having a bifurcated upper end 54^a which straddles the spindle 9 and is adapted to engage the inner face of the cop C, and a horizontally disposed manually engageable arm 55 by means of which the operator may swing the lever E counterclockwise, as seen in Fig. 1 to shift the cop along the spindle, as indicated in dotted lines in that figure.

To facilitate severing the completed cop from the thread T, a thread cutter 56 is secured upon the arm 55 of the lever E. The operator may readily pull the thread into contact with the thread-cutter to sever the thread as she removes the cop from the free end of the winding spindle.

After a cop has been wound and the machine brought to rest automatically, as hereinbefore described, the operator may initiate a new winding cycle by first placing the free end of the thread T between the wires w and then swinging the frame F clockwise as seen in Fig. 4 to shift the wheel 10 into contact with the driver 11. This may be effected by pushing on a thumb piece 57 carried by the forward end of the pin 25. During this swinging movement of the frame F, the abutment member 47 moves upwardly along the stem portion 42^a of the plunger 42, which latter is maintained in its downward position by the spring 44. As the under side of the abutment member 47 clears the shoulder 42^c of the plunger, the spring 49 shifts the abutment member to the left (Figs. 7 and 8) and again places the member 47 above the shoulder 42^c as shown in Fig. 7 to maintain the machine in operation.

Having thus set forth the nature of the invention, what I claim herein is:

1. A cop winding machine comprising a base; a frame pivotally mounted on said base; spring means urging said frame to an inoperative position; locking means working in opposition to said spring means to hold said frame in an operative position; a rotary spindle journaled in said frame and having a thread-receiving end portion designed to have a thread wound thereon; a slide-bar mounted in said frame; a thread-laying finger carried by said slide-bar and having a thread-guide movable adjacent the thread-receiving portion of said spindle; means actuated from said spindle to shift said slide-bar and thread-guide lengthwise of said spindle to cause a thread to be wound helically about the spindle; and means including a trip-finger and a movable abutment actuated thereby actuated by said thread-laying finger, when the thread wound on said spindle has reached a predetermined diameter, to trip said locking means and permit said

frame to be moved to an inoperative position by said spring means.

2. A cop winding machine comprising a base; a frame pivotally mounted on said base; a spindle journaled in said frame; a driving wheel on said spindle; spring means urging said frame to a position in which said wheel is out of driving contact with a driving element; locking means working in opposition to said spring means to hold said frame in a position in which said wheel is in contact with said driving element; a slide-bar mounted in said frame; a thread-laying finger carried by said slide-bar and having a thread-guide movable adjacent said spindle; means including a rotary cam and a bell-crank lever actuated thereby to shift said slide-bar and thread-guide lengthwise of said spindle during the rotation of the spindle to cause a thread to be wound helically about the spindle; and means including a trip-finger carried by said slide-bar and rendered effective by said thread-laying finger, when the thread wound on the spindle has reached a predetermined diameter, to trip said locking means and permit said frame to be moved to a position in which said driving wheel is out of contact with said driving element.

3. A cop winding machine comprising a base; a frame pivotally mounted on said base; a spindle journaled in said frame; a driving wheel on said spindle; spring means urging said frame to a position in which said wheel is out of contact with a driving element located adjacent thereto; locking means working in opposition to said spring means to hold said frame in a position in which said wheel is in contact with said driving element; a stationary brake member carried by said frame adjacent said driving wheel; a slide-bar mounted in said frame; a thread-laying finger carried by said slide-bar and having a thread-guide movable adjacent said spindle; means to shift said slide-bar and thread-guide lengthwise of said spindle during the rotation of the spindle to wind a thread helically about the spindle; and means carried by said slide-bar and rendered effective, when the thread wound on said spindle has attained a predetermined diameter, to trip said locking means and permit said frame to be moved to a position in which said driving wheel is out of contact with said driving element and in contact with said brake member.

4. The combination with a cop winding machine, as set forth in claim 1, of a lever fulcrumed on said frame and having a cop-engaging portion located adjacent the thread-receiving end portion of the spindle; spring means acting on said lever to maintain said cop-engaging portion out of contact with the thread wound on said spindle; and a manually engageable portion formed on said lever by means of which the lever may be turned about its fulcrum to cause the cop-engaging portion thereof to engage a wound cop and shift it lengthwise of said spindle to remove the cop from the spindle.

5. The combination with a cop winding machine, as set forth in claim 1, of a bell-crank lever fulcrumed on said frame and having a bifurcated portion straddling the thread-receiving end portion of the spindle and a horizontally disposed finger portion located below the axis of the spindle; spring means acting on said bell-crank lever to maintain said bifurcated portion out of contact with the thread wound on the spindle, said lever being adapted to be turned about its fulcrum to cause said bifurcated end

to engage a wound cop on the spindle and to shift it lengthwise of the spindle to remove the cop from the spindle; and a thread-cutter carried by said bell-crank lever.

6. A cop winding machine comprising a base; a frame pivotally mounted on said base; spring means urging said frame to an inoperative position; locking means, including a push button, working in opposition to said spring means to hold said frame in an operative position; a rotary spindle journaled in said frame and having a thread-receiving end portion adapted to have a thread wound thereon; a bar mounted for oscillation and endwise translation in said frame; a thread-laying finger carried by said bar and having a thread-guide movable adjacent to and lengthwise of the thread-receiving portion of said spindle; means actuated from said spindle to shift said bar and finger lengthwise of said spindle to cause a thread to be wound helically about the spindle; a spring urging said finger into contact with the thread wound on the spindle; and a trip-finger carried by said bar, and designed when the thread wound on said spindle has reached a predetermined diameter, to engage said push button and trip said locking means, thereby to permit said frame to be moved to an inoperative position by said spring means.

7. A cop winding machine comprising a frame; a power-driven spindle journaled in said frame and held against endwise movement relative thereto; means carried by said spindle to hold a thread-end; a cam journaled on said frame and driven from said spindle; a bell-crank lever journaled on said frame and having a portion engag-

ing said cam to effect oscillations of said bell-crank lever from the rotations of said cam; a slide-bar rockably and endwise slidably mounted in said frame; a thread-laying finger carried by said slide-bar and having a thread-guide movable adjacent and lengthwise of said spindle; means connecting said bell-crank lever with said slide-bar so as to shift said slide-bar and thread-guide lengthwise of said spindle by the oscillations of said bell-crank lever thereby to wind thread helically about said spindle; spring means for rocking said slide-bar about its longitudinal axis in a direction to urge said thread-guide toward said spindle and against the periphery of the thread cop; and means rendered operable by a lengthwise movement of said slide-bar whenever said thread-guide is in a predetermined angular position relative to said spindle to brake said spindle.
